UNITED STATES PATENT OFFICE.

WILLIBERT SIMPSON, OF OTTAWA, ONTARIO, CANADA, ASSIGNOR TO LANDERS, FRARY & CLARK, OF NEW BRITAIN, CONNECTICUT, A CORPORATION OF CONNECTICUT.

CASE FOR VACUUM-RECEPTACLES.

1,191,117.

Specification of Letters Patent. Patented July 11, 1916.

Application filed October 9, 1915. Serial No. 54,997.

To all whom it may concern:

Be it known that I, WILLIBERT SIMPSON, a subject of the King of England, and resident of Ottawa, Province of Ontario, Dominion of Canada, have invented certain new and useful Improvements in Cases for Vacuum-Receptacles, of which the following is a specification.

The object of this invention is to produce 10 a device of the character described having features of novelty of advantage.

The invention relates particularly to a case closed at the bottom and open at the top, and with a novel arrangement and 15 means for securing the sleeve and cap in position, with special reference to the protection of the case from the entrance of liquids.

The drawing is a central vertical section 20 of a case with the sleeve and cap shown separated therefrom, the vacuum receptacle being shown in side elevation.

In the drawings, *a* denotes the case which is tubular and closed at the bottom, the 25 case being conveniently formed by cupping and drawing operations which provide an integral structure. The vacuum receptacle *b* which is customarily made of glass or other fragile material is insertible from the 30 top of the case and is carried in a resilient support or spacer to guard it against breakage from shocks. At the upper end of the case two screw threads are formed, of two different diameters, the lower thread *c* being 35 of greater diameter than the upper thread *d*. By preference the threads are arranged as shown, formed in the metal of the case, and the smaller immediately above the larger.

40 *e* denotes a sleeve apertured at its end to receive and engage the mouth of the receptacle, the lower edge of the sleeve being threaded for engagement with the upper and smaller thread *d* on the case. A point 45 to which I desire to call particular attention is the fact that by preference the sleeve *e* which acts to hold the receptacle in place, overlies the thread *d* in order to prevent the entrance of liquids into the case.

50 *f* denotes a cap inclosing the sleeve *e* and threaded at its lower edge to engage the lower and larger thread *c*. By this con-

struction the cap can be screwed on and off the case without disturbing the sleeve, and consequently without disturbing the security 55 of the receptacle in the case, and at the same time the joint between the sleeve and case is of a nature to prevent the entrance of liquids into the case.

I do not desire it to be understood that 60 the foregoing illustration and description specify the limitations of the invention.

I claim as my invention:

1. A case of the character described, comprising a body portion having at its upper 65 end a plurality of exterior threads of different diameters, a vacuum receptacle located therein, a sleeve having threaded engagement with the thread of smaller diameter and apertured at its upper end to engage said receptacle, and a cap having threaded engagement with the thread of 70 larger diameter.

2. A case of the character described, comprising a body portion having at its upper 75 end a plurality of exterior threads of different diameters, a vacuum receptacle located therein, a sleeve threaded at its lower edge, overlying and engaging with the smaller thread on the case, its upper end 80 being apertured to engage said receptacle, and a cap having threaded engagement with the larger thread.

3. A case of the character described having a plurality of exterior threads of different diameters at its upper end, the smaller thread being arranged immediately above the larger, a vacuum receptacle located therein, a sleeve provided for threaded engagement with the exterior of the 90 thread of smaller diameter and apertured at its upper end to engage said receptacle, and a cap enveloping said sleeve and having threaded engagement with the thread of 95 larger diameter.

4. A case for vacuum receptacles, a sleeve and an inclosing cap, said sleeve and cap being secured to said case exteriorly thereof and independently of one another.

WILLIBERT SIMPSON.
